UNITED STATES PATENT OFFICE.

WALTER M. SCHWARTZ, OF PHILADELPHIA, PENNSYLVANIA, ASSIGNEE TO PROCTOR & SCHWARTZ, INCORPORATED, OF PHILADELPHIA, PENNSYLVANIA, A CORPORATION OF PENNSYLVANIA.

TRAY DRIER.

Application filed July 18, 1921. Serial No. 464,156.

To all who it may concern:

Be it known that I, WALTER M. SCHWARTZ, a citizen of the United States, residing in Philadelphia, Pennsylvania, have invented

5 certain Improvements in Tray Driers, of which the following is a specification.

My invention relates to certain improvements in driers, particularly driers of the type in which the material is placed on trays, 10 although it will be understood that the invention can be applied to machines for drying materials supported by any suitable means.

The object of my invention is to provide means whereby the air in circulation can be automatically reversed at intervals so that the material will be subjected to reverse currents in order to be thoroughly dried.

This object I attain in the following manner, reference being had to the accompanying drawings, in which:

Fig. 1 is a side view of my improved drier; Fig. 2 is a longitudinal sectional view; and

Fig. 3 is a plan view.

Referring to the drawings, 1 is the casing of the drier separated by a zig-zag partition into two compartments. 2 is the drying compartment and 3 is the compartment containing the heating apparatus 4, which, in the present instance, is a series of coils of steam pipes. 5 are angular supports in the drying compartment for the trays 6 on which the material to be dried is placed. The zig-zag partition consists of angular transverse members 7 and valves, or air baffles, 9, 10, 11 and 12. These baffles are arranged in pairs and the two sections are secured to shafts 13, 13^a, respectively, mounted in bearings carried by bars 14, one bar being arranged at an angle to the other, as clearly shown in Fig. 2. On each shaft 13 is an arm 15 and the two arms of each pair are connected by a link 16. On each shaft 13, outside of the casing 1, is an arm 17. The several arms are connected by a vertically arranged rod 18, which is connected at its upper end to an arm 19 on a shaft 20. On the shaft is a short arm 21, which is connected by a link 22 to an arm 23 on a shaft 24. On the shaft 20 is an arm 25 having a pin which projects in the path of a lug 26 on an endless chain 27. On the shaft 24 is an arm 28 having a pin, also in the path of the lug. The shaft 24 is located above the upper

run of the chain and the shaft 20 is located 55 above the lower run of the chain so that the lug first 26 to shift the air baffles alternately. The air baffles, and the levers connecting them, are so arranged that the baffles 9 and 11 are moved to the open position when 60 the baffles 10 and 12 are moved to the closed position, and vice versa.

The chain 27 passes around sprocket wheels 29 and 30 mounted on shafts 31 and 32 mounted in bearings on the frame of 65 the drier. The shaft 31 is the driven shaft and has a worm wheel 33, which meshes with a worm 34 on a short longitudinal shaft 35. This shaft is driven in any suitable manner.

In order to circulate the air in the drier, 70 a fan 36 is provided. This fan is located directly back of the zig-zag partition in the compartment 2, and is mounted on a suitable shaft 37 mounted in bearings and is driven at any speed desired.

By the above construction, it will be seen that the direction of air in circulation can be automatically reversed at given intervals.

In Fig. 2 of the drawings, the baffles 9 and 11 are shown open, while the baffles 10 and 12 are shown closed. The direction of the air currents is shown by the arrows, 75 fig. 2.

The air passes under the several trays and up through the material thereon, some of the 80 air passing outside of the trays, as shown. When the trays are solid, then the air passes through the space between the lower trays to an end chamber 38, returning between the upper trays. When the baffles 9 and 11 are 85 closed and the baffles 10 and 12 are open, then the direction of the air is reversed, the air passing across the upper trays and down through the space between the lower trays.

By regulating the speed of the chain, or 90 placing two or more lugs on the chain at certain points, the reversal of the baffles can be regulated.

I claim:

1. The combination in a drying machine, 100 of a heating compartment; a drying compartment; a partition separating the two compartments; and including two sets of baffles; automatic means for opening one set of baffles and for closing the other set of 105 baffles; and means for circulating air in the two compartments.

2. The combination in a drier, of a casing;

5 a zig-zag partition in the casing dividing the casing into a drying compartment and a heating compartment; a circulating fan for circulating the air through the two compartments; two sets of baffles in the partition; and automatic means for actuating the baffles so that the direction of air currents will be reversed at predetermined intervals.

3. The combination in a drier, of a casing; 10 a zig-zag partition dividing the casing into a drying and a heating compartment; means for circulating air in the compartments; a series of air baffles in the zig-zag partition; and means for automatically operating the air baffles so as to change the direction of the flow of the air at given intervals.

4. The combination in a drier, of a casing; 15 a zig-zag partition therein dividing the interior of the casing into a drying compartment and a heating compartment; means, in the heating compartment, for circulating the air through both compartments; a series of air baffles in the partition; and automatic 20 means for operating the air baffles, two sets of the baffles being open when the others are closed so that the direction of the flow of air through the drier is reversed at given intervals.

30 5. The combination in a drier, of a casing; a partition dividing the casing into a drying compartment and a heating compartment;

ment; means for circulating the air through the two compartments; two sets of air baffles, the baffles being mounted on transverse 35 shafts; arms on the shafts; a rod connecting the several arms; two rock shafts connected together, one of said shafts having an arm connected to the rod, each of said rock shafts having arms thereon with pins; an endless 40 chain having a lug adapted to engage the pins of the said rock shafts; and means for driving the chain so that the rod will be reciprocated and will open two sets of baffles and will close the other two sets. 45

6. The combination in a drier, of a casing having a zig-zag partition therein forming transverse angle plates and baffles, said partition dividing the casing into a drying compartment and a heating compartment; 50 means for circulating the air in the two compartments, the baffles being arranged in pairs, each baffle being mounted on a transverse shaft; means for connecting the shafts of each pair so that they will be opened and closed in unison; an arm on one of the shafts of each pair; a rod connecting the said arms; and automatic means for reciprocating said rod so as to open two sets of baffles and to close the other two sets alternately, 55 in order to change the direction of flow of the air currents through the drier. 60

WALTER M. SCHWARTZ,
